(57) **CLAIM**

An ornamental design for an electrical connector, as shown and described.

DESCRIPTION

FIG. 1 shows a front view of the electrical connector according to the inventive design.

FIG. 2 shows a top plan view of the electrical connector according to the inventive design.

FIG. 3 shows a rear view of the electrical connector according to the inventive design.

FIG. 4 shows a bottom view of the electrical connector according to the inventive design.

FIG. 5 shows a side view wherein each side of the electrical connector is symmetrical and therefore the opposite side view has been omitted.

FIG. 6 shows a cross sectional view of the electrical connector taken along the line 6—6 of FIG. 1; and,

FIG. 7 shows a cross sectional view of the electrical connector taken along the line 7—7 of FIG. 1.
